United States Patent Office

Des. 230,117

Patented Jan. 29, 1974

230,117

PORTRABLE MAT

Andrew Johnson, 3140 N. 12th St.,
Philadelphia, Pa. 19133

Filed Apr. 30, 1971, Ser. No. 139,318

Term of patent 14 years

Int. Cl. D6—09

U.S. Cl. D6—201

FIG. 1 is an isometric perspective view of a portable mat showing my new design in folded position, the side opposite being plain and unornamented;

FIG. 2 is a side elevational view thereof; and

FIG. 3 is a top perspective view of the inner side of the design shown in FIG. 1 when in unfolded position.

I claim:

The ornamental design for a portable mat, as shown.
